Fig. 3

Fig. 4

Fig. 5

FIG. 1 is a perspective view of our design for a convertible heater and cooker while in the closed position; FIG. 2 is a top plan view thereof;

FIG. 3 is a front view in elevation;

FIG. 4 is an end view in elevation;

FIG. 5 is a view in rear elevation;

FIG. 6 is a perspective view of our design depicting the cooking pan in position above the heater; and

FIG. 7 is a perspective view of the heater in the heating position without the cooking pan.

The grid pattern which is particularly shown on the heating surface on FIG. 7 is understood to uniformly repeat on the sides and top of said surface.

We claim:

The ornamental design for a convertible heater and cooker, substantially as shown and described.
